(57) CLAIM

The ornamental design for a support for boating accessories, as shown and described.

DESCRIPTION

FIG. 1 is a first isometric view of the support for boating accessories according to an embodiment of the present invention;

FIG. 2 is a second isometric view of the support for boating accessories of FIG. 1;

FIG. 3 is a side view of a support for boating accessories thereof;

FIG. 4 is an opposite side view of the support for boating accessories thereof;

FIG. 5 is a front view of the support for boating accessories thereof;

FIG. 6 is a back view of the support for boating accessories thereof;

FIG. 7 is a top view of the support for boating accessories thereof; and,

FIG. 8 is a bottom view of the support for boating accessories thereof.

The broken line portion of the figures is included to show unclaimed subject matter only and forms no part of the claimed designs.
